WRINGER HEAD AND DRIVE

Original application filed June 9, 1927, Serial No. 197,721. Divided and this application filed December 31, 1930. Serial No. 505,836.

This application is a division of an application filed June 9, 1927, Serial No. 197,721.

This invention relates to improvements in driving mechanism for power-driven clothes wringers, such mechanisms being commonly known as wringer heads, by means of which wringer rolls manually controlled, in the starting, stopping and reversing operations, while the driving elements or members are in constant motion.

The primary object of the invention is to provide a power-driven clothes wringer with convenient and comparatively simple but highly efficient starting, stopping, and reversing mechanism for the wringer rolls, which mechanism is easily and quickly controlled by a hand lever, and is, therefore, entirely safe. The operator is not liable to be injured by the wringer rolls, or the clothes passing between said rolls to be torn or damaged, when our wringer head is used.

Other objects and advantages will appear in the course of the following description.

We attain the objects and secure the advantages of our invention by the mechanism illustrated in the accompanying drawings, in which:

Fig. 1 is an enlarged end elevation, in partial section, of the starting, stopping, and reversing cam of a wringer head which embodies a practical form of our invention.

Fig. 2 is a top plan of the cap and other members of said wringer head.

Fig. 3 is a central, vertical section through said wringer head, and

Fig. 4 is an enlarged bottom plan of said cam.

Similar reference characters designate similar parts throughout the several views.

Referring first to Fig. 3, it will be seen that the upper portion of a hollow, supporting column is represented at 1, on which is mounted a casing 2 having therein vertical bearings 3—3 in axial alignment with each other, and a horizontal bearing 4, and provided on top with a cap 5. The upper terminal of a driving shaft 6 is journalled in the lower bearing 3. This shaft is driven constantly in one direction from a motor (not shown) or other driving medium, and it is assumed that said

shaft rotates to the right. An end portion of a wringer is represented at 7, and the same is rigidly secured to one end of the casing 2. The wringer is equipped with the usual squeeze rolls, end portions of which appear 55 respectively at 8 and 9.

The roll 8, which is the positively-driven roll, is mounted on a shaft 10 that extends through an opening 11 in the adjacent end of the casing 2, into said casing. That portion 60 of the shaft 10 which is in the casing is angular in cross section. Journalled in the bearing 4 is a collar 13, and extending through said collar is a horizontal shaft 13 which is also angular in cross section. The collar 12 65 and the shaft 13 are pinned or otherwise secured to each other. The shaft 10 is connected with the shaft 13 by means of a coupling 14 and a pin 15 extends through said coupling between adjacent ends of said 70 shafts. The pin 15 and a flange on the collar 12 at the left of the bearing 4 hold the shaft 13 against an excessive amount of longitudinal movement.

There is a small chamber 16 and a large 75 chamber 17, separated by the bearings 4, in the casing 2. The coupling 14 is in the chamber 16, and the shaft 13 extends into the chamber 17. The cap 5 is mounted on the casing 2 over the chamber 17, and is secured 80 to said casing by screws or other means. In the upper part of the cap 5 is a generally oblique slot 18 extending to the left from the forward end. The sides of the slot 18 in their central parts are preferably parallel 85 with the ends of the cap 5, and the end portions of said sides preferably parallel with the said cap ends, as shown in Fig. 2.

At the top of the column 1 is a notched flange 19. The casing 2 rests directly on the top of the column 1 and on the flange 19, and has a hollow, centering extension or stem 20 which is received in and fits said column. The lower bearing 3 is in the stem 20. The casing 2 is rotatable on the column 1, and is secured thereto and released therefrom by means of a downwardly spring-pressed plunger 21 adapted to enter the notches in the flange 19 and to be withdrawn therefrom, and an operating lever 22 for said plunger. 100

Journalled in the upper bearing 3 is a vertical shaft 23 which has at the lower end a lug 24 to enter a transverse slot 25 in the upper end of the shaft 6, so that these two shafts are coupled together. At the upper end of the shaft 23, above the upper bearing 3, is a pinion 26 that extends into the chamber 17, and has on top a projection 27. In the axial center of the pinion 26 is a passage 28 which opens through the top of said pinion, and has therein a spring 29 with a ball 30 supported thereon and protruding from the upper end of said passage. The pinion 26 is revolved in one direction (to the right) by the shafts 23 and 6.

Splined on the shaft 13 is a sleeve 31 shouldered to form hubs 32—32 at the ends, the outer portions of said hubs being screw threaded. Mounted on the hubs 32 are two gears 33, and two nuts 34 which are screwed onto the hubs outside of the gears. The gears 33 have their teeth on the inner sides and adjacent to the peripheries thereof. The construction and arrangement of parts are such that either gear 33 can be caused to intermesh with the pinion 26, and both of the gears can be disposed so that neither intermeshes with said pinion, according to the position of the sleeve 31 on the shaft 13.

Mounted on the sleeve 31, between the gears 33, is a cam 35. The nuts 34 force the gears 33 against the sleeve shoulders and rigidly secure these parts together and the cam 35 is held against independent endwise movement on the sleeve 31. The bottom part of the cam 35 is cut away as best shown in Fig. 1, and there is formed in said part a cam groove 36 into which the upper part of the pinion projection 27 extends, and there are three recesses 37 in the top of said groove to receive the upper part of the ball 30. One of the recesses 37 is in the center of the cam groove 36, and the other two recesses are equal distances from the first on opposite sides thereof. The intermediate portion of the cam groove 36 is oblique and extends to the right from the forward end of said portion, and relatively offset portions of said groove are parallel with the ends of said cam. A lever 38 extends radially from the upper part of the cam 35 and out through the slot 18 in the cap 5. The axis of the lever 38 continued downwardly passes through the center of the middle cam-groove recess 37, and when said lever is erect it is in the center of the slot 18. The slot 18 is of sufficient width to enable the lever 38 to be moved back and forth in and from end to end of said slot, it being necessary that said lever be permitted so to move that it may actuate and travel with the cam 35, as explained below.

Upon swinging the lever 38 forwardly into the position which it occupies in Fig. 2 in the forward end of the slot 18, the cam 35 is partially rotated on the sleeve 31 in the same

direction, and also caused to move to the right by reason of the engagement between the sides of the cam groove 36 and the pinion projection 27 in said groove, and upon swinging said lever rearwardly into the rear end of said groove, said cam is partially rotated on said sleeve in that direction, and also caused to move to the left by reason of the aforesaid engagement. In the first instance the projection 27 initially is in the rear end of the cam groove 36, and in the second instance said projection initially is in the forward end of said groove. During these movements rotatively and longitudinally of the cam 35, the ball 30, under the influence of the spring 29, enters successively the recesses 37, either first leaving the rear recess, entering and leaving the intermediate recess, and entering the forward recess, as the cam 35 is rotated forwardly, or leaving said forward recess, entering and leaving said intermediate recess, and entering said rear recess, as said cam is rotated rearwardly, the lever 38 being rocked to the full extent each time. The ball 30 thus serves as a check to retain the cam 35 at either end of its travel, and also intermediate of said travel because then said ball is in the middle recess.

When the cam 35 is actuated by throwing the lever 38 forwardly to the full extent, said cam is moved on its axis to the right and carries with it the sleeve 31 and the gears 33, thereby causing the left-hand gear to intermesh with the pinion 26. This gear, the sleeve 31, and the shafts 13 and 10 are now rotated in the direction to revolve the wringer rolls 8 and 9 in what may be termed the forward direction. At this time the ball 30 is in the forward recess 37. When the cam 35 is actuated by throwing the lever 38 rearwardly to the full extent, said cam is moved to the left and carries with it the sleeve 31 and the gears 33, thereby causing the right-hand gear to intermesh with the pinion 26. This gear, the sleeve 31, and the shafts 13 and 10 are this time rotated in the direction to revolve the wringer rolls in the reverse direction. Now the ball 30 is back in the rear recess 37. When the lever 38 is moved from either end of the slot 18 to a central position in said slot, the cam 35 is actuated longitudinally into a position intermediate of the ends of its lengthwise travel, and disengages whichever gear 33 is in engagement with the pinion 26, so that neither gear is in engagement with said pinion. The ball 30 is now in the intermediate recess 37. Accidental displacement of the parts is prevented by the ball 30 and the recessed portions of the cam groove 36, and by the lever 38 and one or the other ends of the slot 18, accordingly as said lever be in forward- or reverse-driving position. The dwell formed by the intermediate parallel parts of the groove 18 also as-

sists in holding the parts in neutral position, when the rolls 8 and 9 are idle.

The wringer roll 8 is started in the direction to carry the clothes forward between it and the roll 9, by moving the lever 38 from the transverse center of the slot 18 into contact with the front end of said slot, as in Fig. 2, said rolls are reversed by moving said lever to the back end of said slot, the mechanism then being disposed as in Fig. 3, and said rolls are stopped by moving said lever from either end of said slot into said transverse center, when the lever is erect. The rolls are started in reverse by moving the lever backward from the transverse center of the slot 18. The full stroke of the lever 38 in either direction causes one gear to be moved out of engagement and the other gear to be moved into engagement with the pinion, and one half of said stroke from either end of the slot 18 causes both gears to be positioned out of engagement with the pinion.

Necessarily the slot 18 and the cam groove 36 must be properly proportioned, have the required directions, and be in correct relative arrangement, in order to enable the gears 33 to function in the manner explained above.

More or less change may be made in the shape, size, construction, and arrangement of some or all of the parts of this wringer head, without departing from the spirit of our invention, or exceeding the scope of what is claimed.

We claim:

1. In a wringer head, a casing, a shaft journalled in said casing, and provided with a cam and driven members, a driving shaft located between and adapted to actuate said driven members when either is in engagement therewith, whereby said first-named shaft is rotated in one direction or the other accordingly as one driven member or the other is in engagement with said driving member, means mounted for independent rotary motion on said first-named shaft, and means to cause said first-named means to move longitudinally when moved rotatively, whereby one or the other of said driven members is engaged with said driving member, or both are caused to be disengaged therefrom, and yielding means to retain said first-named means in either of its extreme positions, or its intermediate position.

2. In a wringer head, a casing, a shaft journalled in said casing, and provided with a driving member having a guide member for a cam, a second shaft journalled in said casing, a cam and driven members mounted for endwise movement on said second shaft, said guide member and said driven member being on opposite sides of said driving member, whereby said cam when actuated about its axis is caused to move endwise and carry with it one or the other of said driven members into engagement with, or to position

both of said driven members out of engagement with, said driving member, and means for actuating said cam about its axis.

3. In a wringer head, a casing, a shaft journalled in said casing, and provided with a driving member having a cam guide, a second shaft journalled in said casing, a sleeve splined on said second shaft, driven members mounted on and secured to said sleeve on opposite sides of said driving member, a cam mounted on said sleeve between said driven members, and having a portion in engagement with said guide member, and means partially to rotate said cam, whereby the same, by reason of its engagement with said guide member, is caused to move endwise and carry one or the other of said driven members into engagement with, or to locate both of them out of engagement with, said driving member.

4. In a wringer head, a casing, a shaft journalled in said casing, and provided with a driving member having a cam guide, yielding holding means carried by said driving member, a second shaft journalled in said casing, a cam having a portion to engage said guide, and parts to be engaged by said yielding means, and driven members, said cam and said driven members being mounted for endwise movement on said second shaft, said cam being rotatable to and said driven members rotatable with said second shaft and said cam, when partially rotated, by reason of its engagement with said guide, being caused to move endwise and carry with it one or the other of said driven members into engagement with, or to position both of said driven members out of engagement with, said driving member, and said yielding means being adapted to engage any of the aforesaid parts of said cam, and thereby assist in holding said cam against accidental displacement, and means for actuating said cam about its axis.

5. In a wringer head, a casing having a part within which is a slot, a shaft journalled in said casing and provided with a driving member having a cam guide, a second shaft journalled in said casing, a cam having a portion for engagement with said guide and gears mounted for endwise movement on said second shaft, said cam, when partially rotated, being caused to move endwise and carry with it one or the other of said driven members into engagement with, or to position both of said gears out of engagement with, said driving member, such endwise movement being due to the engagement between said guide and said cam, and an operating lever extending from said cam through said slot.

6. The combination, in a wringer head, with a casing and a shaft journalled in said casing, and provided with a pinion, which pinion has a projection, of a second shaft

journalled in said casing, a cam and gears mounted for endwise movement on said second shaft, said projection being in engagement with said cam, whereby the latter upon rotation, by reason of such engagement, is caused to move endwise and carry with it one or the other of said gears into engagement with, or to position both of said gears out of engagement with, said pinion, and means for actuating said cam manually.

7. The combination, in a wringer head, with a casing, and a shaft journalled in said casing, and provided with a pinion, which pinion has a projection, of a second shaft journalled in said casing, a sleeve mounted on said second shaft, gears mounted on and secured to said sleeve, on opposite sides of said pinion, said sleeve being splined to said second shaft so as to produce a drive from said gears to the shaft, a cam mounted on said sleeve between said gears, and having a groove therein to receive said pinion projection, and means partially to rotate said cam, whereby the same, by reason of its engagement with said projection, is caused to move endwise and carry one or the other of said gears into engagement with, or to locate both of said gears out of engagement with, said pinion, and means for actuating said cam manually.

8. The combination, in a wringer head, with a casing, a shaft journalled in said casing, and provided with a pinion, which pinion has a projection and a spring-pressed ball carried by said pinion and projecting beyond said projection, of a second shaft journalled in said casing, a grooved and recessed cam, and gears, all mounted for endwise movement on said second shaft, said projection being in the groove in said cam, whereby the latter upon rotation, by reason of such engagement, is caused to move endwise and carry with it one or the other of said gears into engagement with, or to position both of said gears out of engagement with said pinion, and said ball being adapted to enter any of the recesses in said cam, and thereby assist in holding the parts against accidental displacement, and means for actuating said cam manually.

9. The combination, in a wringer head, with a casing having a part within which is a slot and a shaft journalled in said casing, and provided with a pinion, which pinion has a projection, of a second shaft journalled in said casing, a cam having therein a groove and gears mounted for endwise movement on said second shaft, said projection being in said groove, whereby said cam upon rotation, by reason of such engagement, is caused to move endwise and carry with it one or the other of said gears into engagement with, or to position both of said gears out of engagement with said pinion, said cam being adjacent to said slot, and the latter having a

reverse but otherwise generally similar outline to that of said groove, and a lever extending from said cam through said slot.

10. The combination, in a wringer head, with a casing, having a part with a slot therein, a shaft journalled in said casing, and provided with a pinion, which pinion has a projection and a spring-pressed ball carried by said pinion and extending beyond said projection, of a second shaft journalled in said casing, a grooved and recessed cam, and gears, all mounted for endwise movement on said second shaft, said projection being in the groove in said cam, whereby the latter upon partial rotation by reason of such engagement is caused to move endwise and carry with it, one or the other of said gears into engagement with, or to position both of said gears out of engagement with said pinion, and said ball being adapted to enter any of the recesses in said cam, and thereby assist in holding the parts against accidental displacement, said cam being adjacent to said slot, and said slot having a reverse but otherwise generally similar outline to that of said groove, and a lever extending from said cam through said slot.

11. In a wringer head, a casing, a shaft journalled in said casing, and provided with a driving member having a guide member for a cam, a second shaft journalled in said casing, a cam and driven members mounted for endwise movement on said second shaft, said guide member and said driven member being on opposite sides of said driving member, whereby said cam when actuated about its axis is caused to move endwise and carry with it one or the other of said driven members into engagement with, or to position both of said driven members out of engagement with, said driving member, means for actuating said cam about its axis, and a column support and a part on said case in rotatable engagement and a part on said case provided with openings for receiving a spring pressed member on said case.

12. In a wringer head, a casing, a shaft journalled at one end in said casing, a cam rotatable in said case supporting an opposite end of said shaft and driven members associated therewith, a driving shaft located between and adapted to actuate said driven members when either is in engagement therewith, whereby said first-named shaft is rotated in one direction or the other accordingly as one driven member or the other is in engagement with said driving member, means mounted for independent rotary motion on said first-named shaft, and means to cause said first-named means to move longitudinally when moved rotatively, whereby one or the other of said driven members is engaged with said driving member, or both are caused to be disengaged therefrom, and

yielding means to retain said first-named means in either of its extreme positions, or its intermediate position.

5 In testimony whereof we affix our signatures.
